UNITED STATES PATENT OFFICE

151,418

DESIGN FOR A FACSIMILE RECORDER

Walter Dorwin Teague, Annandale, N. J., assignor to Finch Telecommunications, Inc., Passaic,
N. J., a corporation of Delaware

Application October 22, 1946, Serial No. 134,156

Term of patent 14 years

(Cl. D26—14)

To all whom it may concern:

Be it known that I, Walter Dorwin Teague, a citizen of the United States, residing at Annandale, in Hunterdon County and State of New Jersey, have invented a new, original, and ornamental Design for a Facsimile Recorder, of which the following is a specification, reference being had to the accompanying drawings, forming a part thereof.

The figure is a view in perspective of a facsimile recorder showing my new design.

The left side of the cabinet is identical in appearance with the right side shown. The back of the cabinet is plain.

I claim:
The ornamental design for a facsimile recorder, as shown and described.

WALTER DORWIN TEAGUE.
